US00D946677S

(12) **United States Design Patent** (10) **Patent No.:** **US D946,677 S**
(45) **Date of Patent:** **** Mar. 22, 2022**

(54) **GOLF CLUB HEAD**

(71) Applicant: **KARSTEN MANUFACTURING CORPORATION**, Phoenix, AZ (US)

(72) Inventor: **Anthony D. Serrano**, Anthem, AZ (US)

(73) Assignee: **Karsten Manufacturing Corporation**, Phoenix, AZ (US)

(**) Term: **15 Years**

(21) Appl. No.: **29/738,658**

(22) Filed: **Jun. 18, 2020**

(51) LOC (13) Cl. **21-02**

(52) U.S. Cl.

USPC **D21/743**

(58) **Field of Classification Search**

USPC **D21/736-746, 759**

CPC **A63B 53/00; A63B 53/04; A63B 53/007; A63B 53/065; A63B 53/048; A63B 60/00; A63B 60/04**

See application file for complete search history.

Primary Examiner — Mitchell I. Siegel

(57) **CLAIM**

The ornamental design for a golf club head, as shown and described.

DESCRIPTION

FIG. 1 is a top perspective view of a golf club head; FIG. 2 is a bottom perspective view of the golf club head of FIG. 1; FIG. 3 is a top view of the golf club head of FIG. 1; FIG. 4 is a bottom view of the golf club head of FIG. 1; FIG. 5 is a front view of the golf club head of FIG. 1; FIG. 6 is a rear view of the golf club head of FIG. 1; FIG. 7 is a heel side view of the golf club head of FIG. 1; and, FIG. 8 is a toe side view of the golf club head of FIG. 1. The broken line showing is included for the purpose of illustrating unclaimed subject matter and forms no part of the claimed design.

1 Claim, 7 Drawing Sheets
